UNITED STATES PATENT OFFICE.

HIRAM STEVENS MAXIM, OF LONDON, ENGLAND.

AUTOMATIC GUN.

SPECIFICATION forming part of Letters Patent No. 436,899, dated September 23, 1890.

Application filed April 8, 1890. Serial No. 347,100. (No model.) Patented in England December 1, 1886, No. 15,734; in Belgium October 15, 1887, No. 79,005; in Italy November 26, 1887, No. 22,500; in France December 14, 1887, No. 185,641; in Austria-Hungary April 21, 1888, No. 34,166; in Germany August 24, 1888, No. 44,208, and in Spain January 25, 1889, No. 8,895.

To all whom it may concern:

Be it known that I, HIRAM STEVENS MAXIM, a citizen of the United States, residing at London, England, have invented certain new and useful Improvements in Machine or Automatic Guns, (for which I have obtained Letters Patent as follows: in Great Britain, No. 15,734, dated December 1, 1886; in France, No. 185,641, dated December 14, 1887; in Germany, No. 44,208, dated August 24, 1888; in Austria-Hungary, No. 34,166, dated April 21, 1888; in Italy, No. 22,500, dated November 26, 1887; in Spain, No. 8,895, dated January 25, 1889, and in Belgium, No. 79,005, dated October 15, 1887,) of which the following is a specification, reference being had to the accompanying drawings.

This invention relates to automatic or machine guns, and more particularly to guns of this class invented and patented by me, which are operated by force created by the explosion in the barrel, and wherein the barrel and breech-block are arranged to slide longitudinally in a stationary frame or support and are locked together during the earlier part of the recoil, and the said block is then unlocked or released from the barrel and moved backward therefrom to extract the empty cartridge-shell and permit the introduction of a fresh cartridge between the breech-block and the rear end of the barrel.

The present invention consists in mechanism of novel construction for effecting the operation of the gun in substantially this manner. This mechanism comprises an arrangement of hydraulic or hydropneumatic cylinders and pistons by means of which the energy of the recoil of the barrel is stored and rendered available for returning the barrel to its original or firing position, by which also the force of the forward or return movement of the barrel is utilized to continue the backward movement of the breech-block after it is unlocked from the barrel, and by which, finally, the energy of the said forward movement of the barrel and continued backward movement of the breech-block is stored and rendered available for returning the breech-block to its normal or forward posi-

tion. The devices directly co-operating to produce these results are improvements or modifications of other devices invented by me for the same purpose.

My present application involves, however, other features of novelty, chief among which are an improved cartridge-feeding mechanism and other details, which will be more fully described hereinafter.

In the drawings annexed, Figure 1 is a longitudinal central section of a gun constructed in accordance with my invention and provided with my new hydropneumatic apparatus for effecting the requisite movements of the barrel and breech-block. Fig. 2 is a sectional plan of the same. Fig. 3 is a transverse section on line *x* *x*, Fig. 1. Fig. 4 is a detail view of a valve hereinafter described. Fig. 5 is a longitudinal section of a portion of the gun, showing a modification of my invention. Fig. 6 is a transverse section on line *y* *y*, Fig. 5. Fig. 7 is also a section on line *y* *y*, Fig. 5, showing the parts in the positions which they occupy at the termination of the recoil.

A is a strong casing or frame; B, the barrel supported thereby and capable of a limited movement in said frame in line with its axis. The casing or stationary frame is provided with trunnions A', by which it is mounted.

C is a sliding breech-block that is capable of a longitudinal movement with the barrel and of a further backward movement after the barrel has reached the limit of recoil.

In the gun shown in Figs. 1 to 3 the breech-block C is provided with vertically-sliding blocks or pieces C', which have teeth or projections C'' formed thereon. The barrel B is formed with extensions B', which have corresponding teeth or projections B'', with which the projections C'' on the sliding pieces C' are adapted to engage, and thus lock the breech-block to the barrel. The sliding pieces C' have, moreover, lateral projections D formed thereon, which in the recoil will slide upon inclined faces D' on the frame A, so that the pieces C' will be moved upward and their projections C'' disengaged from the pro-

jections B" on the barrel, thereby unlocking the breech-block from the barrel. The projections D will slide in the grooves D". In the return movement of the breech-block the 5 projections D will slide upon a switch E, pivoted at E' to the frame A, so that the pieces C" will be held up until the barrel has returned to the firing position, when the said pieces will fall and again lock the breech-block to the barrel. The breech-block C is guided in its to-and-fro movement by projections F on the said block fitted to slide in guideways F' in the frame A.

F" is a vertically-sliding bar working in guides in the breech-block C. A lever c, pivoted at c' to the breech-block, has its short arm connected by a pin or stud to the slide F" and its long arm connected to the sliding piece C', so that in the operation of unlocking the breech-block from the barrel the sliding piece C' will turn the said lever c upon or about its pivot, and thereby operate the slide F" for the purpose hereinafter described.

G is the firing-pin, which is acted upon by a spring G' for driving the breech-block C. H is a sear pivoted at h and adapted to engage with the short arm of a lever h', to the long arm of which a lanyard is to be attached 30 for firing the gun by hand. In the recoil the sliding bar F" acts upon the sear H and forces the firing pin into its cocked position. A spring H' then acts upon the lever h' and causes the said lever to engage with the bent lever g, and thus hold the firing pin in its cocked 35 position until released by pulling of the said lanyard. By the downward movement of the sliding bar F" the sear g" will be caused to enter a notch g' in the firing pin when the 40 said pin is moved back by the sear H, and will thus hold the said firing pin until the breech-block is locked to the barrel and the said sliding bar is moved upward.

The breech-block is provided with extracting-hooks H', to draw the cartridges into position to be fed into the barrel, and with other extracting-hooks G', arranged to slide in grooves in the side of the breech-block and adapted to extract the empty cartridge-shell 50 from the barrel. An opening is provided in the under side of the frame A through which the empty cartridge-shells may fall from the gun.

To provide for unlocking the breech-block 55 by hand when necessary, hollow bosses I are formed on the frame A, and bevel wheels K are provided, having elongated hollow bosses k, which fit into the hollow bosses I. Screw-threaded rods k' are fitted into corresponding internal screw-threads in the hollow bosses k, and are provided with projections k", which engage with the under side of lateral projections on the sliding piece C'. The bevel-wheels K are geared with bevel-wheels K', 65 fixed on a shaft K", which is supported in brackets secured to the bosses I. The shaft K" is moreover provided with hand-wheels

I', by which the said shaft may be rotated to raise the sliding piece C' and unlock the breech-block from the barrel.

L is a cylinder attached to the frame A and provided with a piston L', the rod L" of which works in a stuffing-box in the rear end of the cylinder L and is firmly secured to a projection I" on the barrel. The rear end of the 70 said cylinder L is connected with the forward end thereof by means of a pipe or passage J, provided with a valve l. The piston L' is perforated and has firmly attached thereto a pipe l', working in a stuffing-box in the front end 75 of the cylinder L and having a valve l" in its rear end. The front end of the pipe l' is provided with a stuffing-box, through which is passed a pipe i. The pipe i is adapted to slide on the pipe l' and forms, in combination 80 therewith, a telescopic joint. The pipe i has at its rear end a valve i', which is provided with a stem i", adapted to act upon the valve l", as and for the purpose hereinafter described. The pipe J is extended beyond the 85 front end of the cylinder L and communicates through a valve j with the pipe i', which is, moreover, connected by means of branch pipes j' with the front ends of a pair of hydraulic cylinders J', firmly secured to the frame A and 90 fitted with pistons, the rods I' of which are secured to projections J" on the breech-block C. The rear ends of the cylinders J' are connected by means of pipes m with air vessels 95 or receivers Z, firmly secured to the frame A. 100

M M are hydraulic buffers fitted with rams M', which are secured to the extensions B' of the barrel B. The rear ends of the said buffers are attached to and communicate with an air chamber or receiver M", so that in the recoil the liquid in the hydraulic buffers M will be forced into the receiver M" and will compress the air therein, and when the force of the recoil is expended the air in the said receiver will expand and force the liquid into 110 the hydraulic buffers, thus moving the barrel forward into the firing position. If desired, the air in the receiver M" may have an initial compression imparted thereto by forcing air into the said receiver.

In combination with each hydraulic buffer I employ a double valve for regulating the flow of liquid to and from the receiver M". The valve-seat m' is formed with a central spindle m", upon which is fitted to slide a 120 valve n, acted upon by a spring n', which tends to press it against its seat. A cap a' is screwed on the end of the central spindle m". By turning this cap in either direction the lift of the valve n may be regulated. The 125 pressure exerted on the said valve by the spring n' may be regulated by means of a screw-nut a, fitted upon the said cap a'. The forward end of the central spindle m" has a valve a" fitted to slide thereon, and is provided with a nut b, for regulating the lift of the said valve. In the recoil of the barrel the pressure of the liquid in the hydraulic buffers will close the valve a", so that the 130

liquid must pass through openings b' and annular grooves b'' in the valve-seat m' . The said liquid will therefore act upon the valve n , thereby compressing the spring n' and opening the said valve to allow the liquid to flow into the receiver M'' . In the forward or return movement of the barrel the spring n' will react and close the valve n , so that the liquid must flow through the openings c in the said valve and openings c' in the valve-seat m' into the hydraulic buffer M .

Z' is a casing, which forms a part of the gun-frame A , and into which the cartridges are to be fed by hand at Z'' .

15 To provide for the automatic raising of the cartridges into position to be drawn back by the extractors H'' , so that they will fall into position to be thrust into the barrel by the breech-block in the forward movement, I provide an elevator comprising a drum Y , fitted to rotate in suitable bearings in the casing Z' , and a corresponding drum Y' , fitted to rotate on the barrel. These drums are arranged to work an endless chain Z'' , provided

25 with hooks or curved projections Y'' . The drum Y has one of its journals formed with internal teeth, as at X , with which gears a pinion X' , fixed on a shaft X'' , supported in a bracket W , attached to the casing Z' . A

30 crank-handle z is fitted on the end of the shaft X'' for the purpose of operating the elevator by hand. To provide for the automatic operation of the said elevator the drum Y' is formed with internal grooves $z' z''$. The

35 grooves z' extend in a direction parallel with the axis of the barrel, while the grooves z'' are made of spiral form, and each groove z'' extends from the front end of one of the grooves z' to the rear end of one of the adja-

40 cent grooves z' . The barrel is provided with a projection W' , which in the recoil of the barrel will work in one or the other of the grooves z'' and cause the drums $Y Y'$ to rotate through a distance equal to the pitch of

45 the said grooves. In the forward movement of the barrel the projection W' will slide in one or other of the grooves z' and not rotate the drum Y . The elevator will therefore be operated only during the recoil of the barrel.

50 The operation of the gun shown in Figs. 1 to 4 is as follows—that is to say: The parts are shown in the position which they occupy when the breech is closed. In starting the gun the breech-block is unlocked from

55 the barrel by hand by means of the hand-wheels I' and screws k' , and the said block is moved away from the barrel a short distance by forcing liquid into the front ends of the cylinders J' by means of a hand-pump

60 suitably connected therewith. A number of cartridges are then fed into the elevator at Z'' and raised by turning the crank-handle z . As soon as a cartridge has arrived above the barrel the breech-block is driven home to

65 cause the hooks H'' to engage with the head of the said cartridge. The breech-block is then moved back and draws the said car-

tridge out of the elevator. When the said block has reached its rearmost position, the said cartridge will be released and will fall 70 into position to be fed into the barrel. The breech-block is then forced forward into its firing position by the expansion of the air in the receiver Z and is again locked to the barrel by means of the hand-wheels I' and screws k' . The gun may then be fired by pulling the lanyard attached to the lever h' . In the recoil the projections D slide up the inclined guideway D' , and thereby raise the sliding piece C' and unlock the breech-block 75 from the barrel. The rams or plungers M' force the liquid from the hydraulic buffers M through the double valves into the chambers M'' , thereby compressing the air therein, which when the gun has terminated its recoil reacts upon the liquid in the said chamber and forces the barrel forward into its firing position. The piston L' and the pistons in the cylinders J' are moved backward with the breech-block and the barrel in their recoil, thus creating a partial vacuum in the front of the cylinders L and J' . The liquid in the rear of the cylinder L is forced through the valve l and pipe J partly into the front of the said cylinder and partly through the 80 valve j into the front of the cylinders J , thereby filling the space left by the rearward movement of the pistons. In the forward or return movement of the barrel the liquid in the front of the cylinder L is forced through the pipe J and valve j into the cylinders J' and acts upon the pistons in the said cylinders, thereby causing the same to continue their backward movement and compressing the air in the rear of the said cylinders J' and 85 forcing it into the receivers Z . The breech-block is thus caused to continue its rearward movement while the barrel is moving forward. The valve i' in the pipe i is at the same time kept closed by the pressure of the water in the said pipe. As soon as the barrel has returned to its firing position the stem i'' of the valve i' strikes the valve l'' and opens the said valve, thus allowing the liquid to flow through the piston L' into the rear of 90 the cylinder L . The compressed air in the receiver Z will then react upon the pistons in the cylinders J' and force the liquid from the front of the said cylinders through the said valve l'' , thereby driving the breech-block home. The breech-block is then automatically locked to the barrel, as above described.

It will be seen from the foregoing description that in each recoil of the gun the empty cartridge-shell is extracted from the barrel, a fresh cartridge drawn from the elevator, and the said elevator is caused to rotate, so as to bring another cartridge into position to be drawn therefrom in the next recoil, as above described.

In Figs. 5, 6, and 7 I have shown a modification of my invention, wherein I employ a breech-block which is formed of two parts N

N', the front part N' of which has hooks or projections for engaging with the flange of a cartridge in the barrel to effect the extraction of the empty cartridge-shell. The rear part N is V-shaped and is arranged to slide up and down on the part N'. When the breech is closed, the part N will fit into a groove N'' in the extension B' of the barrel, and thus lock the breech-block to the barrel. The 10 said V-shaped piece N is held down by a spring O, bearing at its upper end against a projection O' on the part N' and fitted at its lower end in a recess in the part N. The part N is formed with lateral studs 15 provided with friction-rollers O'', which in the recoil will ride up inclined surfaces P on the outer frame A, thus compressing the spring O, raising the part N, and unlocking the breech-block from the barrel. A lever or 20 catch o is pivoted to the front part N' of the breech-block and is acted upon by a spring o', whereby it is caused to enter a notch o'' in the part N of the breech-block when the said part is raised, as above described. A pin 25 or stud P' is fixed in the frame A in such a position that when the breech-block has terminated or nearly terminated its forward movement the said lever or catch o will strike the said pin or stud and thereby be disengaged 30 from the V-shaped piece N. The said piece will then be forced downward by its spring O and will lock the breech-block to the barrel.

In Figs. 5, 6, and 7 I have also shown the application to my improved gun of means for 35 firing the same by electricity. For this purpose a contact-pin or rod w, provided with an enlarged end, is fitted in the part N' of the breech-block and is acted upon by a spring w', which tends to keep it out of contact with a cartridge in the barrel. A wire or conductor w'' is secured in the conical opening v in the part N of the said block, so as to form a spring, which acts upon a horizontal pin or rod v', and when the breech-block 45 is locked to the barrel presses the said pin or rod against the contact-pin w, which is thus moved into contact with the cartridge in the barrel. The said wire or conductor w'' will thus be electrically connected with the cartridge through the pin or rod v' and the spring contact-pin w. A hollow rod or plunger v'' is fitted in a recess in the extension B' of the barrel and is acted upon by a spring u. This plunger carries a conductor 50 u', which is held by the spring u in contact with the conductor w'' while the breech-block is locked to the barrel. The conductor u' is connected with one pole of a battery or other electric generator. The other pole of the 55 said battery is connected through the barrel with the cartridge-shell. Therefore, as soon as the breech-block is locked to the barrel the necessary connections will be made for firing the gun by means of electricity. The 60 cartridges used must be constructed in any well-known or suitable manner, so that they can be exploded by electricity.

It is obvious that the devices hereinbefore described for locking the breech-block to the barrel and unlocking it therefrom are applicable to guns arranged to operate without the aid of hydraulic apparatus. 70

What I claim is—

1. In an automatic or machine gun, the combination, with a frame or support, of a barrel 75 capable of sliding longitudinally therein, one or more hydraulic cylinders and pistons connected with the barrel, and reservoirs containing air connected with the cylinders and intermediate valve mechanism, whereby the air is compressed in said receivers by the recoil of the barrel, as set forth.

2. In a machine-gun, the combination, with a frame or support, of a longitudinally-movable barrel, hydraulic cylinders secured to 85 the frame, pistons therein connected to the barrel, a reservoir at the rear of the frame communicating with the cylinders, and spring-valves between the cylinders and the reservoir, said valves being constructed, substantially as set forth, to oppose the passage of the liquid from the cylinders to the reservoirs, but to permit it to return more freely. 90

3. In a machine-gun having a sliding barrel and breech-block, the combination, with 95 said breech-block, of a movable portion, projections thereon that engage with corresponding projections on the barrel and normally lock the breech-block to the barrel, lateral extensions on said movable portion of the 100 breech-block, and inclined faces on the frame of the gun with which said extensions engage in the backward movement of the barrel and by means of which the movable part of the breech-block is disengaged from the 105 barrel, as set forth.

4. The combination, with the sliding breech-block, of a part vertically movable therein, lugs or projections thereon adapted to engage with corresponding projections on the barrel 110 when the breech-block is in its normal position, lateral extensions on said movable part, stationary inclined guides or faces with which the said projections engage, and a pivoted switch under which the projections slide on 115 the backward movement of the barrel and over which they return to the firing position of the breech-block, as set forth.

5. The combination, with a stationary-gun frame and a barrel capable of longitudinal movement therein, of a breech-block adapted to slide with the barrel and capable of a longer course of movement than the barrel, and extractor-hooks carried by said breech-block, one set of which is in position to engage with a cartridge in the magazine and the other set to engage with that in the barrel, as herein set forth. 120 125

6. The combination, with the vertically-movable portion of the breech-block normally engaging with the barrel for locking the breech-block thereto, of threaded rods working in the gun-frame and having projections that engage with the said movable part when 130

the breech-block is locked and means for raising the rods by hand, whereby the breech-block is unlocked, as set forth.

7. In a machine-gun having a sliding barrel and breech-block movable therewith, the combination of a cylinder and perforated piston connected with the barrel, one or more cylinders and pistons connected to the breech-block, and valve-controlled passages of communication between the forward ends of the cylinders connected to the breech-block and the forward and rear ends of that connected with the barrel, whereby the return of the barrel to its firing position after recoil will operate to drive back the pistons connected with the breech-block and compress the air in the cylinders in which they work, as herein set forth.

8. The combination, with the sliding barrel and breech-block of a machine-gun, of two drums, one turning around the barrel, the other mounted below the barrel, an endless chain or belt passing around said drums and provided with hooks or projections for elevating cartridges to a position to be engaged by the breech-block, and means for imparting an intermittent movement to the drums, as set forth.

9. The combination, with the sliding bar-

rel and breech-block of a machine-gun, of a 30 drum surrounding the barrel and a drum mounted beneath the barrel, the former being provided on its interior with connected grooves alternately parallel with and oblique to the axis of the barrel, a projection on the barrel 35 adapted to enter said grooves and impart to the drum a given movement around the barrel at each recoil, and an endless chain or belt for elevating the cartridges passing around said drums, as set forth.

10. In a machine-gun having a sliding barrel and breech-block, the combination of a system of hydropneumatic cylinders, pistons working therein and connected, respectively, with the barrel and the breech-block, and 45 valve-controlled passages of communication between the cylinders, substantially as set forth, whereby the return of the barrel after recoil and the forward movement of the piston connected therewith will continue the 50 backward movement of the pistons connected with the breech-block and store energy in the cylinders in which said pistons work, substantially as set forth.

HIRAM STEVENS MAXIM.
